LYNN A. KNIPP, OF LOS ANGELES, CALIFORNIA

ROTARY CABINET

Application filed November 16, 1929. Serial No. 407,735.

This invention relates to cabinets and more especially to the class including a case and an enclosed rotary carrier with multiplex compartments.

5 An object of this invention is to provide an improved bearing device about which the carrier is rotative on a vertical axis; it being a purpose to provide a trunnion lug of very low cost and neat and inconspicuous form 10 and which permits the ready installation of structural parts of the cabinet.

A further object is to provide a rotary carrier cabinet which may be incorporated either in portable or in built-in apparatus.

15 The invention consists in certain advancements in this art as set forth in the ensuing disclosure and having, with the above, additional objects and advantages, and whose construction, combination and details of 20 means, and the manner of operation will be made manifest in the ensuing description of the herewith illustrative apparatus; it being understood that modifications, variations and adaptations may be resorted to within the 25 scope, principle and spirit of the invention as it is more directly claimed hereinafter.

Figure 1 is a perspective of a portable form of the cabinet.

Figure 2 is a horizontal section of a built-in 30 form of cabinet.

Figure 3 is a fragmentary vertical section showing the trunnions in detail.

The casing structure includes a top element 2 and a bottom element 3 spaced vertically a 35 suitable distance and of a size desired according to the particular utility intended. Side walls 4 and a semicircular back shield 5 form a chamber in which there is mounted a rotary carrier having a top 6 and a bottom 7 of like-size discs having coaxial trunnions fixed to the top and bottom elements 2 and 3.

These trunnions each comprise a tubular lug 10 fixed by a wood-screw 11 to the respective case element; the lugs lying substantially flush in apertures 12 in respective top and bottom parts of the carrier, Fig. 3.

The carrier is provided with variously arranged vertical partitions 13 extending inwardly from the edges of the discs and intersecting to form divers compartments

which are vertically divided by horizontal shelves 14 at various elevations.

The back-guard wall is of an arc complementary to the cylindrical carrier so that as this is rotated articles thereon may not 55 be lost outward.

In Fig. 1 the portable cabinet has a front door 15 hinged to a side wall but when the cabinet is of the built-in type, Fig. 2, the case has front wing panels 17—17 extending 60 toward each other and forming a front opening at which may be exposed a part of the carrier provided with a flat door 18 which will lie in the plane of the panels and form a harmonious, flush trim therewith. Either 65 door may be used on either cabinet type.

Drawers 20 are provided as desired in the carrier and a feature of the device includes a secret compartment 21 with a door 22, this being concealed by the stack of drawers. 70

To obtain strong construction and to prevent drag of the bottom 7 on the floor 3, a metallic shim 23 is secured by wood-screws 24 to the floor and the trunnion lug is fixed to the shim by its bolt-screw 11. 75

What is claimed is:

A cabinet structure including a case, a rotary carrier disposed and turnable on a vertical axis in said case and provided with shelves and partitions and having substantially cylindrical form, a flat door attached to one side of the carrier, and said case having front wing panels extending toward each other to form, with the said door, a flush front closure for the cabinet. 85
